CLAIM

The ornamental design for a storage carrying case bag, as shown and described.

DESCRIPTION

FIG. 1 is a front perspective view of a storage carrying case bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is an enlarged detail view taken from portion 9 of FIG. 1;

FIG. 10 is an enlarged detail view taken from portion 10 of FIG. 2; and,

FIG. 11 is an enlarged detail view taken from portion 11 of FIG. 2.

The broken lines in the drawings depict portions of the storage carrying case bag that form no part of the claimed design.
